UNITED STATES PATENT OFFICE.

CLOICE B. BAKER, OF ST. LOUIS, MISSOURI, ASSIGNOR OF ONE-HALF TO WILLIAM BAWDEN, OF ST. LOUIS, MISSOURI.

TENDER-HOSE COUPLING.

1,069,638.

Specification of Letters Patent.

Patented Aug. 5, 1913.

Application filed June 13, 1912. Serial No. 703,432.

To all whom it may concern:

Be it known that I, Cloice B. BAKER, a citizen of the United States, residing at St. Louis, Missouri, have invented a certain 5 new and useful Improvement in Tender-Hose Couplings, of which the following is a full, clear, and exact description, such as will enable others skilled in the art to which it appertains to make and use the same, 10 reference being had to the accompanying drawings, forming part of this specification.

My invention relates to new and useful improvements in pipe couplings and particularly to such couplings as are utilized 15 in the tubular connections between a locomotive boiler and tender. These connections usually include a metallic pipe carried by the locomotive and a section of flexible tubing carried by the tender and it is the principal object of my invention to provide a simple, inexpensive coupling for the adjacent ends of the tubular connections just 20 mentioned and which coupling is capable of being quickly connected or disconnected.

A further object of my invention is to provide a coupling of the class described that is perfectly water tight when connected and said coupling being provided with 25 means adapted to lock the two parts thereof to each other so that said parts are effectually and firmly held together regardless of the jolting and vibration to which the coupling is subjected in service.

To the above purposes my invention consists in certain novel features of construction and arrangement of parts hereinafter more fully described and claimed.

Figure 1 is a side elevation of a coupling of my improved construction. Fig. 2 is a plan view of the coupling. Fig. 3 is a horizontal section taken on the line 2-2 of Fig. 1.

Referring by numerals to the accompanying drawings, 1 designates a metallic pipe and 2 the flexible hose, which parts are 45 united by my improved coupling.

3 designates a shell that is substantially hemispherical in form and provided with an 50 internally threaded nipple 4 which receives the threaded end of the pipe 1. Formed within the shell 3 just below its edge is an annular rib or flange 5 which forms a seat for the edge of a strainer 6 of perforated 55 metal or suitable wire mesh. Formed on

top of the shell 3 is an outwardly projecting bifurcated lug 7 and formed on the opposite side of said shell and projecting forwardly therefrom is a horizontally disposed ear or lug 8 that is provided with an opening 9.

10 designates a shell, the main body portion of which is substantially like the shell 3 and formed on or fixed to said shell is a tubular extension 11 which receives the end 65 of the flexible tube 2. Formed on the inside of the shell 10 around the edge thereof and projecting outwardly therefrom is a continuous flange 12, which, when the parts of the couplings are united, extends into the 70 chamber within the shell 3 immediately adjacent to the edge of the strainer 7. This flange 12 forms a support for a packing ring or gasket 13 that occupies a position between the edges of the shells 3 and 10 75 when the same are united. Formed on the sides of the shell 10 are lugs 14 provided with notches 15, which latter serve as seats for the sides of a split ring 16. This ring is made in the form of a yoke having an extension 17 on its solid side, which extension 80 fits in the opening 9 when the parts are assembled. The split side of the ring 16 is provided with a pair of lugs 18 and pivotally connected to these lugs by means of 85 a pin 19 is the bifurcated end of a bolt 20, which latter passes through the bifurcated lug 7 and its threaded end receives a nut 21. The purpose of splitting the ring or yoke 16 is to enable it to be sprung over the ends 90 of the lugs 14 so that the side portions of said yoke or ring can be seated in the notches 15. After the yoke or ring has thus been seated in the notches 15, the ends provided with the lugs 18 are brought together and 95 connected to the bifurcated end of the bolt 20.

When the two parts of the coupling are to be connected, the shell 10 is brought into position immediately in front of the shell 3 100 and the extension 17 is inserted through the opening 9. The bolt 20 is now swung downward into position within the bifurcated lug 7 after which the nut 21 is tightened upon said bolt, thus drawing the upper end of 105 the split ring toward the bifurcated lug and causing the sides of said split ring to fulcrum on the lugs 14, thereby exerting equal pressure entirely around the contacting faces of the shells 3 and 10. The packing 110

ring or gasket 13 positioned between said contacting faces is by this action compressed and thereby forms a tight joint between parts 3 and 10. To disconnect the parts of the coupling, the nut 21 is loosened until the bolt 20 can be swung upward out of the bifurcated lug 7 and the shell 10 can now be disengaged from the shell 3 by lifting the extension 17 from the opening 9. The split ring or yoke 16 and the bolt 20 provide simple means for firmly connecting the two parts of the coupling and forming a water tight joint between the contacting faces of said members and the entire coupling is comparatively simple, comprises a minimum number of parts and forms an efficient coupling for the tubular connections between a locomotive boiler and tender.

While I have described my improved coupling as being particularly intended for use in the tubular connections between a locomotive boiler and tender, it will be readily understood that practically the same form of coupling may be advantageously used between the adjacent ends of tubes wherever a readily detachable coupling is desired.

It will be readily understood that minor changes in the size, form and construction of the various parts of my improved coupling can be made and substituted for those herein shown and described without departing from the spirit of my invention, the scope of which is set forth in the appended claim.

I claim:

In a coupling of the class described and in combination, a pair of tubular members having complementary faces to oppose each other with packing therebetween, one of said

members being adapted to be secured to a rigid support and having a perforated lug 40 on one side and a bifurcated lug on its opposite side, said perforated lug projecting substantially parallel to the axis of the members with the perforation extending transversely to the direction of length of the lug, 45 said perforation being positioned in advance of the face of the member by which it is carried, a split ring carried by the other member and formed with a projection operating as a male element with respect to said 50 perforation, said latter member being adapted to be secured to a flexible supporting member, said ring also having a swinging element adapted to engage the bifurcated lug on the rear face of the latter, said ring- 55 carrying member having notched lugs to receive and form a fulcrum for the ring when the members are coupled, said bifurcated lug having its face extending at substantially right angles to the axis of the members to 60 act to prevent disengagement of the members under vibratory action, said swinging element being in the form of a threaded bolt carrying an element adapted to unyieldingly contact with said lug rear face by 65 movements longitudinally of the bolt when said element is in engagement with said rear face, whereby said members may be coupled by the use of one hand.

In testimony whereof I hereunto affix my 70 signature in the presence of two witnesses, this 11th day of June, 1912.

CLOICE B. BAKER.
